UNITED STATES PATENT OFFICE.

MARTIN V. MEHREN, OF CHICAGO, ILLINOIS, ASSIGNOR TO STRONGHART COMPANY, OF CHICAGO, ILLINOIS, A CORPORATION OF ILLINOIS.

POCKET SAVINGS-BANK.

1,280,517.

Specification of Letters Patent.

Patented Oct. 1, 1918.

Application filed June 10, 1915. Serial No. 33,302.

To all whom it may concern:

Be it known that I, MARTIN V. MEHREN, a citizen of the United States, residing at Chicago, in the county of Cook and State of Illinois, have invented a certain new and useful Improvement in Pocket Savings-Banks, of which the following is a full, clear, concise, and exact description, reference being had to the accompanying drawings, 10 forming a part of this specification.

My invention relates to pocket savings banks especially adapted to contain small coins such as dimes, nickels, cents, and the like.

15 Prominent objects of the invention are to provide a simple and practical form of pocket savings bank; to simplify the construction and reduce the cost of manufacture; to arrange for the easy opening of the 20 bank by an authorized person, but to prevent opening by unauthorized persons; to arrange for the ready re-assembling and re-locking of the bank, and to accomplish the foregoing and other desirable results in a simple and 25 practical manner.

In the accompanying drawings—

Figure 1 is a vertical section of a pocket savings bank embodying my present invention;

30 Fig. 2 is a horizontal section taken on line 2—2 of Fig. 1;

Fig. 3 is a section taken between the flanges 3 and 4 looking toward the spring 10;

35 Fig. 4 is a plan view of a special key or device for unlocking the bank; and

Fig. 5 is a partial horizontal section similar to Fig. 2, showing a modified form of locking means and key for operating the same.

40 Referring first to Figs. 1 to 3, the bank shown for carrying out the invention comprises a bottom member 1 and a top member 2, which members may be of any convenient form but are desirably circular, as shown in

45 Fig. 2. The bottom member 1 is provided with an upstanding annular rim 3 and the top member 2 with a downwardly-extended annular rim 4. These rims 3 and 4 are of corresponding shape and of such size that

50 the rim 4 may fit and slide telescopically within the rim 3. These rims 3 and 4 are provided with longitudinal slots forming, when the rims are in place, a coin slot 5 by which coins may be introduced into the interior of the bank. The inner rim 4 is pro-

vided with a series, as for example three, as shown, of bayonet slots 6 having side slot openings 7 which extend to the bottom of said rim 4. The outer rim 3 is provided with a corresponding series of prongs or 60 projections 8 which are adapted to fit in the slots 6 and to be inserted into the same by means of the side slots 7. Thus, the top 2 and bottom 1 may be put together by fitting the rims 3 and 4 telescopically together at a 65 place where the lugs or prongs 8 will slide into the apertures or slots 7 and then turning said top and bottom members relatively to one another so that the prongs 8 move out of register with the slots 7 and thereby 70 hold said top and bottom members from separation as long as the prongs 8 are out of register with the side slots 7. In order to lock the top and bottom members in this condition when desired, I provide a locking device 75 which is preferably in the nature of a member 10 having a slot 11 adapted to engage one of the prongs 8 whereby said prong will be normally engaged and held against movement, thereby holding the top and bottom 80 members against relative rotary movement and maintaining the same in locked condition. The member 10 is preferably a spring-like member, as for example, a strip 12 of spring material secured by rivets 13 to the 85 inner rim 4, the end 15 of said spring member being conveniently bent inward, as shown in Fig. 2, so as to permit the insertion of some implement or device between the end 15 and the inner surface of the rim 90 4, whereby said member 10 may be sprung or moved outward sufficiently to permit the prong 8 to become disengaged from the slot or aperture 11. As a preferred arrangement, this end 15 is located adjacent to and at one 95 side of the coin slot or opening 5, whereby a tool or key may be inserted in the coin slot and caused to actuate the spring member 10.

In Fig. 4 I show a preferred construction of tool or key, the same being designated by 100 the numeral 16. This key 16 comprises a main or body part and a prong 16^a separated from the main or body part by a slot 17 of about the thickness of the walls of the bank, whereby the key 16 may be placed, as indicated in dotted lines in Fig. 2, with the prong 16^a passed through the coin slot 5, and then said key 16 may be moved to the right (Fig. 2), so as to cause the prong 16^a 105 to slide between the end 15 and the inside of 110

the rim 4, and thereby spring inwardly the end 15 and so cause the member 10 to become disengaged from the prong 8. Thus, when this is done the two members 3 and 4 will be unlocked, thereby permitting a relative rotation of the same so as to bring the prongs or lugs 8 back into register with the transverse slots 7 and thereby permit the top and bottom members to be separated from one another. This permits the bank to be opened and any coins inside to be dropped out.

As a preferred arrangement, I also place a collar 19 outside of the outer rim 3, which collar is loose but fits snugly over the outer rim 3 and is desirable in order to cover up the punched-out portions 20 made in the rim 3 when the lugs 8 are formed by punching out parts of said rim. The outer collar or band 19 is also provided with a slot registering with the coin slot 5 and is also provided with small lugs or projections 21 fitting against the ends of the coin slot 5 so as to hold said band or collar 19 in proper position.

It will be seen that the bank in its closed and locked condition gives no indication of the manner in which it may be unlocked, but that this may be readily done by inserting the key 16 into a suitable opening in the wall of the bank, as for example, into the coin opening 5. By inserting the key, and sliding it a little to one side so that the prong 16a slips under the end of the spring clip 10, the bank is instantly unlocked so that the interlocking bayonet joint devices on the rims 3 and 4 may be disengaged by a slight manual rotation of the top and bottom relatively to one another. These separable parts, in this case consisting of the top and bottom, may then be separated manually, and the coins removed. The bank may be readily closed and locked, without the use of a tool, by simply placing top and bottom together so that the bayonet joints engage one another and then rotating top and bottom relatively to cause clip 10 to engage one of the prongs 8, whereupon the bank is automatically locked in closed condition. It will be understood that when these small banks are given out by a banking institution the latter will ordinarily retain the unlocking key and unlock banks as they are brought in to have their contents deposited.

In the modification of Fig. 5, the spring 10 is provided with an aperture 25, and a key 26 is provided, having a hooked end 27 which can be inserted into the aperture 25. The key 26 is provided with a handle 28 which can be held in the hands while the shank of the key is being inserted in the coin slot 17 (or other opening). A guard 29 is also provided near the end of the spring 10 to prevent access to the end of said spring.

Thus in this device the spring 10 cannot be operated by the key 16 or similar tool, but only by a key with a hooked end or the like. Tampering is thereby more effectually prevented.

It will be understood that changes and modifications may be made without departing from the spirit of the invention.

What I claim is:

1. A bank comprising in combination, relatively rotatable members adapted to form a coin receptacle and to be separated from one another to open such receptacle, one of said members being provided with bayonet joint slots and the other member with projections adapted to fit into said slots when said members are placed together, and also to move into the side extensions of said slots when said members are relatively turned, and means for engaging one of said projections to hold said members against relative rotation.

2. A pocket savings bank comprising top and bottom members provided with contiguous telescoping rims having bayonet-joint interlocking devices, and means for retaining said interlocking devices in engagement, said means comprising a spring clip constructed to engage one of the locking devices and located adjacent the coin slot, whereby a key may be inserted in the coin slot to actuate said clip to unlock said locking device.

3. A pocket savings bank comprising top and bottom members provided with telescoping rims the inner one of which is provided with bayonet slots and the outer one of which is provided with prongs to engage said bayonet slots, a spring clip secured to the inner side of the inner rim and having an aperture to engage one of said prongs, and located adjacent the coin slot whereby a key may be inserted in the coin slot to actuate said clip to disengage it from said prong.

4. A pocket savings bank comprising top and bottom members provided with telescoping rims the inner one of which is provided with bayonet slots and the outer one of which is provided with prongs to engage said bayonet slots, a spring clip secured to the inner side of the inner rim and having an aperture to engage one of said prongs, and located adjacent the coin slot whereby a key may be inserted in the coin slot to actuate said clip to disengage it from said prong, and an outer collar or band surrounding the outer one of said rims.

5. In a bank-structure, the combination of relatively rotatable receptacle-forming sections, one of said sections containing a recess, a lug on the other of said sections adapted to enter said recess and interlock with the section containing said recess when said lug is moved to a position out of regis-

tration with the latter, and locking means engaging said lug for locking said sections against relative rotation to a position in which said lug registers with said recess.

- 5 6. In a bank-structure, the combination of relatively rotatable receptacle-forming sections, one of said sections containing a recess, a lug on the other of said sections adapted to enter said recess and interlock
- 10 with the section containing said recess when said lug is moved to a position out of registration with said recess, and locking means on the one of said sections containing said recess adapted to engage said lug for releasably locking said sections against relative rotation to a position in which said lug registers with said recess.
- 15 7. In a bank-structure, the combination of relatively rotatable receptacle-forming sections, one of said sections containing a recess, a lug on the other of said sections adapted to enter said recess and interlock with the section containing said recess when the lug is moved to a position out of registration with the latter, and locking means on the one of said sections containing said re-

cess adapted to automatically engage said lug and releasably lock said sections against relative rotation to a position in which said lug registers with said recess upon the act 30 of assembling said parts and relatively rotating them, and releasable for permitting separation of said cover-section from said body-section.

8. A bank comprising in combination relatively rotatable members forming a coin receptacle or chamber and adapted to be separated from one another to open said chamber or receptacle, bayonet joint interlocking devices comprising slots with side 40 extensions on one of said members and projections adapted to enter said slots on the other member, and means for engaging one of said projections to hold said members against relative rotation and thereby maintain the bank in locked condition, said bank being provided with a slot or aperture through which a tool or key may be inserted.

In witness whereof, I hereunto subscribe my name this 5th day of June A. D., 1915. 50

MARTIN V. MEHREN.
